Attorneys.

UNITED STATES PATENT OFFICE

EARL N. McCLURE, OF CHICAGO, ILLINOIS

GOLF BALL CONTAINER

Application filed November 8, 1928. Serial No. 317,914.

My invention relates to a golf ball receptacle, and particularly to a receptacle for golf balls which is adapted to be secured to or mounted upon the golf bag. One object is the provision of a receptacle of the type described which shall serve also as handle for the bag. Another object is the provision of improved means for permitting the manual removal of one of a series of golf balls while preventing the escape of any other balls of the series during the removal of one such ball. Another object is the provision of means for preventing the undesired escape of golf balls from the container, while permitting ready insertion of golf balls into the container and easy removal, manually, of golf balls from the container. Other objects will appear from time to time in the course of the specification and claims.

I illustrate my invention more or less diagrammatically in the accompanying drawings, wherein—

Figure 1 is a side elevation with parts in section;

Figure 2 is a section on an enlarged scale along the line 2—2 of Figure 1;

Figure 3 is a longitudinal axial section through the golf ball container;

Figure 4 is a section along the line 4—4 of Figure 3;

Figure 5 is a view similar to Figure 3 with the parts in different position; and

Figure 6 is a detail.

Like parts are indicated by like symbols throughout the specification and drawings.

A generally indicates a golf bag, the details of which form no part of the present invention. Counted upon the upper edge A¹ of the bag is the golf ball receptacle herein shown as the tube B. The tube B is shown in full line in Figure 1 in position to serve as a handle for the golf bag. When so used, its upper portion is surrounded by the strap or band B¹ locked or secured as at B² and expanded or spread as at B³. B³ to engage the edges of the bag. Any suitable means may be employed for securing the upper part of the tube to the golf bag but I illustrate it herein, as in Figure 2, as secured to the upper band or ring of the bag, as by the rivets B⁴. It

will be realized that I illustrate this primarily as an example, it being realized that I do not wish to be restricted to this specific disposition or securing means. When the device is used for a handle I may employ the boot C for the lower end of the tube, the boot being provided with a flexible strap or thong C¹ which may be riveted or bolted or otherwise secured as at C² to the bag.

If it is desired to dispense with the employment of the tube B as a handle the securing means may be reversed and the tube be positioned within the bag.

Turning to the golf ball receptacle and the control means therefor, the tube B is provided with a bottom E against which is compressed the coil spring E¹ which tends, in the form herein shown, to thrust the balls upwardly. The positioning of the discharge aperture at the upper end of the tube is preferred, but it will be realized that a practical exemplification of my invention may be produced in which the balls are removed from the lower end of the tube or at some point in the tube other than the upper end. However in the form shown herein the balls are upwardly thrust by the coil spring E¹.

Preferably the balls are manually removable and I provide the means, shown in detail in Figures 3 to 6 inclusive, whereby the admission of the balls to the tube is made easy while the removal of the balls from the tube can be manually effected, the balls being removed one by one. The upper end of the tube is indicated as cut away as at E² to permit ready manual access to the upper ball of the series. This ball, however, is normally held in position against the thrust of the spring E¹ by the mechanism below described.

Referring particularly to the control mechanism I employ at each side of the tube identical stop elements, generally indicated as G each such element being pivoted, intermediate its ends, as at G¹, the pivot penetrating the cavities G³ in the opposed walls of the housing G². The member terminates at its lower end in a solid stop portion G⁴. It has pivoted to its upper end the stop element G⁵ at the ends of which are the anti-friction members or rollers G⁶. The opposite end of the

member G^5 has secured to it the coil spring G^7 the opposite end G^8 of which is secured in relation to the member G or its pivot G^1 . G^{10} indicates any suitable yielding means, herein shown as a spring, whereby the stop member generally indicated as G is held in the position shown in full line in Figure 3.

It will be realized that whereas I have described and shown a practical and operative device, nevertheless many changes might be made in the size, shape, number and disposition of parts without departing from the spirit of my invention. I therefore wish my description and showing to be taken as in a broad sense illustrative or diagrammatic rather than as limiting me to my specific showing.

The use and operation of my invention are as follows:

20 A series of balls may be thrust into the opening of the tube. As each ball is manually thrust downwardly into the tube it engages the anti-friction members G^6 on the stop element G^5 and tilts that stop element G^5 into the position shown in dotted line at the left of Figure 3. Thus the balls are admitted to the tube without disturbing the general position of the member G , the spring G^7 being weaker than the spring G^{10} . Once the ball 30 has penetrated past the member G^5 that member springs back into the full line position of Figure 3 and is in effect rigid in relation to the member G , so far as upward thrust in response to the spring E^1 is concerned. The thrust of the spring E^1 is insufficient to overcome the spring G^{10} , and the balls are normally held against release.

When the user wishes to remove a ball he grasps it, the apertures E^2 admitting his fingers, and pulls it upwardly against the anti-friction members G^6 and the levers G^5 on which they are mounted. In response to this manually applied upward movement of the ball the members G are tilted into the position shown in full line in Figure 5. That is to say, the member G^5 , with its anti-friction rollers G^6 , is thrust back out of the line of movement of the ball, whereas the member G^4 is thereby rotated into the line of movement of the remaining balls, preventing their upward movement, as shown in Figure 5. When the ball has been completely removed the members G snap back into the full line position of Figure 3 and the series of balls is upwardly moved, by the spring E^1 , until the uppermost or outermost ball of the series engages the anti-friction elements G^6 .

The tube B may be removed from the golf bag if desired.

60 This can be done by loosening the bolt B^2 and its nut in such fashion that the tube may be slid upwardly through the collar B^1 . In such case it is removed from the boot C .

I claim:

55 1. The combination with a golf bag of a

combined handle and golf ball carrier, including a rigid tube secured to and spaced from the upper portion of the bag, said tube having a dispensing aperture and being adapted to contain golf balls. 70

2. The combination with a golf bag of a combined handle and golf ball carrier, including a rigid tube secured to and spaced from the upper portion of the bag, said tube having a dispensing aperture and being adapted to 75 contain golf balls, and means for normally preventing the passage of golf balls through said aperture.

3. The combination with a golf bag of a golf ball carrier, such carrier including a 80 tube normally secured in relation to said bag, said tube having a dispensing aperture at its upper end and means for normally preventing the passage of golf balls therethrough, and a shoe for the lower end of said tube, and a connection between said shoe and the golf bag. 85

4. The combination with a golf bag of a golf ball carrier, such carrier including a tube normally secured in relation to said bag, said tube having a dispensing aperture at its 90 upper end and means for normally preventing the passage of golf balls therethrough, and a shoe for the lower end of said tube, and a flexible connection between said shoe and the golf bag. 95

5. As a new article of manufacture a golf ball receptacle including a tubular member adapted to receive a series of golf balls stacked one upon the other and having a dispensing aperture for the balls, dispensing means mounted adjacent said aperture normally preventing the passage of golf balls from within the tube outwardly through the aperture while permitting balls to be passed inwardly through said aperture, said dispensing means including a movable stop member having a portion engaging the outermost ball of the series to prevent its escape from the tube, and a second portion movable across the path of movement of the remaining balls in the tube in response to thrust upon the first mentioned portion of the stop member incident to manual outward movement of the outermost ball, the tube adjacent said stop member being provided with ball 110 exposing openings whereby the balls may be grasped for movement past the stop member. 115

6. As a new article of manufacture, a golf ball receptacle including a tubular member 120 adapted to receive a series of golf balls stacked one upon the other and having a dispensing aperture for the balls, dispensing means mounted adjacent said aperture normally preventing the passage of golf balls from within the tube outwardly through the aperture while permitting balls to be passed inwardly through said aperture, said dispensing means including a movable stop member having a portion engaging the outer- 125 130

most ball within the tube to prevent its escape from the tube, spring means associated with the stop member and normally engaging said ball engaging portion in yielding engagement with the outermost ball, said stop member having a second portion movable against the tension of said spring means across the path of movement of the remaining balls in the tube in response to thrust upon the first mentioned portion of the stop member incident to manual outward movement of the outermost ball, the tube adjacent said stop member being provided with ball exposing openings whereby the balls may be grasped for movement past the stop member.

7. As a new article of manufacture a golf ball receptacle including a tubular member adapted to receive a series of golf balls stacked one upon the other and having a dispensing aperture for the balls, dispensing means mounted adjacent said aperture normally preventing the passage of golf balls from within the tube outwardly through the aperture while permitting balls to be passed inwardly through said aperture, said dispensing means including a pivotally mounted stop member having a portion extending across the aperture and engaging the outermost ball within the tube, said stop member having a second portion movable to a position extending across the aperture and engaging the next adjacent ball in response to thrust upon the first mentioned portion of the stop member incident to manual outward movement of the outermost ball, spring means associated with the stop member and functioning to yieldably maintain the same with the first mentioned ball engaging portion of the stop member extending across the aperture and the second mentioned ball engaging portion being retracted to leave the aperture clear, the tube adjacent said stop member being provided with ball exposing openings whereby the balls may be grasped for movement past the stop member, and antifriction means mounted upon the ball engaging end of the first mentioned portion of the stop member whereby to facilitate the passage of balls to and from the tubular member.

8. As a new article of manufacture a golf ball receptacle including a tubular member adapted to receive a series of golf balls stacked one upon the other and having a dispensing aperture for the balls, dispensing means mounted adjacent said aperture normally preventing the passage of golf balls from within the tube outwardly through the aperture while permitting balls to be passed inwardly through said aperture, said dispensing means including a pivoted stop member, an arm carried by the stop member on either side of its pivot, said arms being alternately movable across the aperture of

the tubular member when the stop member is rocked on its pivot, the outermost arm being pivotally connected to the stop member, spring means maintaining said pivoted arm projecting laterally from the stop member, additional spring means maintaining the stop member with the pivoted arm extended across the dispensing aperture in engagement with the outermost ball of the series, said pivoted arm yielding inwardly to permit a free passage of balls into the tube, the tube adjacent said stop member being provided with ball exposing openings whereby said balls may be grasped for outward movement, the stop member yieldably rocking on its pivot due to thrust upon the outermost arm by the outward movement of the ball to dispense said ball and to move the inner arm across the aperture to retain the other balls within the tubular member.

Signed at Chicago, county of Cook and State of Illinois, this 6th day of November, 1928.

EARL N. MCCLURE.
